US00D808069S

(12) **United States Design Patent** (10) **Patent No.:** **US D808,069 S**
(45) **Date of Patent:** **** Jan. 16, 2018**

(54) **STAGE LIGHTING**

(71) Applicant: **Martin Professional ApS**, Aarhus N (DK)

(72) Inventors: **Uffe Kjaergaard Toft**, Højbjerg (DK); **Jes Vestergaard**, Brabrand (DK)

(73) Assignee: **Martin Professional ApS**, Aarhus N (DK)

(**) Term: **15 Years**

(21) Appl. No.: **29/554,224**

(22) Filed: **Feb. 9, 2016**

(30) **Foreign Application Priority Data**

Oct. 12, 2015 (EM) 002819375

(51) **LOC (11) Cl.** **26-05**

(52) **U.S. Cl.**

USPC **D26/152**

(57) **CLAIM**

The ornamental design for stage lighting, as shown and described.

DESCRIPTION

FIG. 1 is a perspective view of stage lighting showing our new design;

FIG. 2 is a front elevational view thereof;

FIG. 3 is a side elevational view of one side thereof;

FIG. 4 is a top plan view thereof;

FIG. 5 is a side elevational view of the opposite side thereof;

FIG. 6 is a bottom plan view thereof; and,

FIG. 7 is a perspective view thereof shown with the remainder of the stage lighting in broken lines.

The broken line showing forms no part of the claimed design.

1 Claim, 3 Drawing Sheets
